CIRCUIT BREAKER

Herbert J. Crabbs, Wilkinsburg, and Carl A. Ringbloom, Turtle Creek, Pa., assignors to Westinghouse Electric & Manufacturing Company, East Pittsburgh, Pa., a corporation of Pennsylvania

Application August 30, 1934, Serial No. 742,096

12 Claims. (Cl. 200—169)

Our invention relates to circuit interrupters and is particularly concerned with electrical switches of the type used for isolating or section- 5 alizing portions of a transmission or distribution system.

Switches of this type are generally known as disconnecting switches and have found wide application in present-day transmission and distribution systems, both for the purpose of positively isolating certain equipment or certain 10 portions of a circuit, in order to permit maintenance work to be done thereon, and for the purpose of interconnecting systems which meet at a common point such as a sub-station. Due 15 to the large number of these devices which are used on even a small system, it is desirable that they be relatively inexpensive to manufacture. At the same time, however, the safety of costly 20 equipment and of the individuals working on the line often depends entirely upon the switches, and it is imperative that they be absolutely safe and reliable in operation.

To further complicate the problem of providing an absolutely safe switch which shall not be 25 unreasonably costly, disconnecting switches are frequently mounted outdoors and are, therefore, subjected to extremely adverse weather conditions, particularly in the northern states where ice and sleet formations occur. As a result, a 30 commercially successful device must be extremely rugged and must be positively operable even when frozen or when wet, due to rain or other causes. Further, it is also more or less common practice to mount these switches upon the tops of poles 35 or upon sub-station structures, and it is, therefore, necessary that they shall be operable from one position to the other by a hook-stick or similar device.

The principal object of our invention is to provide 40 an improved disconnecting switch which shall be inexpensive to manufacture, absolutely safe and reliable in operation, and which will be suitable for applications wherein it must be mounted in a more or less inaccessible place.

In the interests of safety, it is imperative that 45 the blade structures of switches of the type under consideration must be securely latched against any movement which might be produced by magnetic stresses or the like when the switch is in the closed-circuit position, and the only satisfactory method so far developed in the art for 50 accomplishing this is to provide a positive latch which directly engages the blade structure when the switch is in the closed-circuit position. Many 55 of the prior art latching arrangements are com-

plicated, unreliable, and unduly costly, and the provision of an improved latching means for disconnecting switches generally is another object of our invention.

A third object of our invention is to provide a disconnecting switch according to the above-mentioned principal object which shall be provided with an improved, positive latching means which shall be readily releasable by movement of the operating member during the initial stages 10 of the circuit-opening operation.

A further object of our invention is to provide an improved high-capacity disconnecting switch which shall be provided with a plurality of 15 separate blade assemblages and a plurality of separate latching members, the entire structure being completely operable through the movement of a single operating member.

Another further object of our invention is to provide a double-throw disconnecting switch 20 which shall be provided with a separate latching means for holding the blade in either of the two positions of the switch, and with means whereby the movement of a single operating member will effect the release of either of the latches.

An additional further object of our invention is to provide a latching means for an electrical switch which shall be so positioned that it will not be effected by the magnetic reactions set up 25 when current flows through the switch.

An ancillary object of our invention is to provide an improved latch for use with disconnecting switches or other equipment which shall be cam-operated.

These and other objects of our invention will 35 be made more apparent in the following description of a preferred embodiment of our invention. Referring to the drawings:

Figure 1 is an elevational view of a double-throw, multiple-blade disconnecting switch 40 wherein are embodied the principal elements of our invention;

Fig. 2 is a plan view of the switch structure shown in Fig. 1;

Fig. 3 is a front elevational view of the operating member used in the switch shown in Figs. 1 and 2;

Fig. 4 is a side elevational view of the member shown in Fig. 3;

Fig. 5 is a fragmentary perspective view showing the details of the latch and the switch operating member of the switch illustrated in the other figures of the drawings;

Fig. 6 is a fragmentary plan view of a single blade switch which includes the novel latching 55

arrangement shown in the device illustrated in Figs. 1 to 5;

Fig. 7 is a front elevational view of a modified switch operating member, particularly intended for use with vertically mounted switches of the type illustrated in the other figures of the drawings; and

Fig. 8 is a side elevational view of the member shown in Fig. 7.

10 The preferred embodiment of our invention comprises a base member 1 which may be formed from a channel-shaped section of structural steel, or the like, three spaced insulators 5 which are bolted onto the channel-shaped base 1 by suitable 15 stud bolts 3, a blade assemblage 7, a contact means 11, which includes a pair of spaced contact tongues 12, for pivotally supporting the blade assemblage on the central insulator 5, and two sets of spaced contact tongues 13 which are 20 adapted to be engaged by the blade assemblage 7 when the switch is in either of the two closed-circuit positions. The contact tongues 13 and the contact means 11 for pivotally supporting the blade assemblage are bolted to suitable cap 25 members 15, one of which is rigidly affixed to the upper end of each of the three insulators 5. A pair of latch means 17, each of which is supported upon one of the outer insulators 5, is provided for latching the blade assemblage 7 in 30 either of the two closed circuit positions.

The blade assemblage 7 comprises two pairs of spaced parallel blade elements 9, each of which is formed from a flat sheet of conducting material, preferably copper. A suitable circular opening is punched in the right-hand end (Fig. 2) of each of the separate blade elements in order to permit the passage therethrough of the bolts 19 which form the pivotal support means for the blade assemblage proper. These bolts extend 40 through similar openings in the upstanding tongue portions 12 which serve to support the blade means, and the contact pressure between the inner opposed surfaces of each of the two sets of parallel blade elements 9 and the cooperating 45 supporting tongue 12 is provided by spring washers 21 interposed between the bolt fastenings and the blades.

A second bolt 23 extends through each of the two parallel blade sections adjacent the unpivoted end of the blade assemblage. These bolts 23, in conjunction with spring washers 25, serve to provide the contact pressure between the blade elements 9 and the cooperating contact tongues 13 which are supported upon the outer 55 insulators. A third bolt 27 extends through each of the two sets of blade elements 9 adjacent the extreme outer end thereof, these bolts 27 serving as supports for the operating member 29, which is shown particularly in Figs. 3 and 4.

60 Two pairs of diverging guide members 31 are bolted upon the cap portion 15 of each of the two outer insulators 5 for aiding in guiding the movement of the switch blade during the operation of the switch, and the contact tongues 13 65 are provided with suitable cut-out portions 33 for accommodating the bolts 23.

A circular opening 35 is punched in the outer unpivoted end of each of the blade elements 9 in order that the blade assemblage may be latched 70 against movement when the switch is in either of the closed circuit positions. While these openings are shown in Fig. 5 as being formed in all four of the blade elements, this arrangement is followed only because it permits the use of a 75 standard blade element for each of the four sepa-

rate blade sections, it being necessary to provide the openings 35 only in the two inner blade elements.

Each of the two latching means 17 which operates with these openings 35 in the blade elements comprises, as is shown particularly in Fig. 5, a pair of latch members 37, each of which is pivotally supported upon the cap portion 15 of the associated insulator and is biased toward the latched position by a suitable coil spring 39. Each of the opposed side portions 41 of the operating member 29 is provided with a projecting portion 43 having a cam surface 45 thereon, these portions 43 being adapted to extend into the same openings in the blade members which are engaged by the latch members 37 when the switch is in the closed circuit position (i. e., the openings 35). The dimensions of the openings 35, the latching members 37, and the cam portions 43 of the operating member 29 are so correlated that the latch members 37 may move freely to the fully latched position during the circuit-closing operation without interference from the cam portions.

During the initial stages of the circuit-opening operation, these cam surfaces 45 on the projecting portions 43 are adapted to engage cooperating cam surfaces 47 formed on the latch members 37 and to move those members out of engagement with the cooperating openings 35 in the blade elements 9, thereby effecting the unlatching of the blade assemblage and permitting the switch to be moved to the open circuit position. The movement of each of the latch members 37 toward the latched position under the action of the associated biasing springs 39 is limited through the engagement of a projecting portion 49 formed integral therewith and the support therefor. It is necessary to limit the motion of the latch in order to assure that the switch shall be relatched during every closing operation.

The cap portion 15 of each of the three insulators 5 is provided with a suitable terminal member 51 in order to permit the switch to be readily interconnected into an electrical circuit.

The switch is shown in one of the two closed-circuit positions in Fig. 1. To open the switch or to move the blade assemblage 7 to the other closed-circuit position, a hook-stick or other device is inserted into the operating eye 53 of the switch operating member 29, and that member is moved in a clockwise direction about its pivot point—the bolts 27. This movement brings the cooperating cam surfaces 45 and 47 of the latch members 37 and the projecting portions 43 of the operating member 29 (which portions extend into the openings 35 formed in the blade elements 9) into engagement with each other, and when the operating member 29 has been moved so that the projecting cam portions 43 engage the lower side of the cooperating openings 35 in the blade elements 9, the adjacent latch members 37 have been moved entirely out of engagement with the blade elements. The blade assemblage 7 is thus free to move under the action of the operating force which is transmitted through the operating member 29.

It should be noted that the operating member 29 is freely movable upon the bolts 27 which comprise the supporting means therefor, and it is thus impossible to rotate the blade assemblage 7 until the projecting cam portions 43 of the member 29 have been moved a distance sufficient to release the latches 37. Thus, the release of the latches 37 takes place automatically.

during the initial stages of the opening operation, and it is not possible to rotate the blade assemblage 7 until the latches 37 have been released.

5 By inspection of Figures 1 and 5, it will be seen that the operating member 29 is movable a rather considerable amount with respect to the blade assemblage 7 during each opening operation of the switch, the limits of this independent motion being defined by the engagement of the cam portions 43 with the sides of the circular openings 35. The cam surfaces 45 on the projecting portions 43 engage the cam surfaces 47 so that the release of the latches 37 is effected 10 during the initial portion of the movement of the operating member 29 independently of the blade assemblage 7. This arrangement permits the latter portion of this movement to be used for producing a prying action on the blade assemblage 7 which serves to start that assemblage in motion and thereby facilitates the opening operation of the breaker. The reaction force of the latch biasing springs 39 is usually sufficient to initiate this prying action, and in addition the 15 heel portion at the lower end of each of the latch members 37 opposite the projection 49 as shown in Fig. 5 rigidly engages the adjacent plate on top of the cap member 15 immediately following the disengaging of the blade assemblage by the 20 latch of which it forms a part. These portions thus serve to provide stops for the latches, and the maximum possible prying action necessarily results.

Following the release of the latch members 37, the blade assemblage may be moved either to the open-circuit position or into engagement with the other set of contact tongues 13 supported upon the right-hand insulator. When the blade assemblage 7 is being moved into engagement 25 with either of the sets of contact tongues 13, it is necessary to move the operating member 29 so that the projecting cam portions 43 abut against the upper surfaces (with respect to the base 1) of the openings 35 formed in the blade elements 9. This assures that the latch releasing means is in a position where it in no way interferes with the latching movement of the latch members during the circuit closing operation. Thus, as the blade assemblage is moved 30 into either of the two closed circuit positions, the latch members 37 automatically engage the blade assemblage, without interference from the latch releasing means. The obvious result, of course, is to provide an absolutely fool-proof structure 35 which may not be operated in an incorrect or undesired manner. When the blade assemblage is moved to the closed-circuit position, it is positively latched in and the latches cannot be released until the operating member 29 is moved in the circuit opening direction.

The cam action of the operating member 29 and the latches 37 is particularly effective in breaking ice which may be formed on the switch during the winter time, and for that reason little difficulty will be experienced in operating the switch under almost any conditions. The outer end of each of the two sets of parallel blade elements is free to move laterally on the bolts 27 which serve to support the operating member 29, and the switch is thus made full-floating, which means that the blade elements are capable of movement toward each other in order to compensate for wear, or the like, during its operation.

Two sets of parallel blades and two latches on 35 each of the spaced conducting members have

been shown in the structure. It is, of course, a comparatively simple matter to utilize almost any number of blades, since the form of latch release mechanism which we have disclosed lends itself readily to a multiple blade construction. It is also possible to utilize only a single blade element, the latch releasing mechanism being very suitable for this type of switch as well.

Each of the latch members 37 is movable in a plane which is substantially at right angles to the normal plane of movement of the blade means. Also, the entire latch structure is disposed outside of the space between the tongues 12 and 13 and, therefore, out of the normal conducting path through the switch. By this arrangement, all magnetic stresses on the latches which might be produced by very heavy overload currents flowing through the switch are entirely obviated and an absolutely safety operation is assured under all possible conditions. If desired, the latch structure may be insulated from the stationary contact portion, but this is not absolutely necessary, since the right angle disposition of the paths of movement of the latch and the blade obviates any possibility of the latch being opened when the switch is in operation.

The structure shown in Fig. 6 is essentially similar to that shown in the other figures of the drawings, except that a single pair of parallel blade elements have been utilized. When this is done, it is of course, unnecessary to utilize a bifurcated operating member. The blade elements 109 are essentially similar in form to those shown in the previously described device. The operating member 129 is pivotally supported upon a bolt 127 which extends through both of the opposed blade elements. The latch 137 engages an opening 135 in the side of one of the blade elements and is movable substantially at right angles to the plane of movement of the blade 40 assemblage, and both of the blade elements are full-floating. The construction of the guide horn 131, and the single bolt 123 and the two spring washers 125 for securing contact pressure between the inner surfaces of the blade means and the cooperating contact tongue 113 are substantially similar to those in the structure already described.

The modified operating member 229 shown in Figs. 7 and 8 is particularly intended for use with vertically mounted, single throw switches. By positioning the eye portion 253 at an angle, with respect to the shank portion 241, the engagement of the operating member by the hook stick or other device is greatly facilitated and the effective leverage of the operating member is increased. This modified structure is provided with a projecting portion 243 and a cam surface 245, which correspond to the portions 43 and 45 of the member 29.

In the foregoing we have described the structural features and the mode of operation of a novel disconnecting switch which possesses numerous advantages over the structures previously known in the art. Our improved switch utilizes an improved latching arrangement which positively latches the blade against movement when the switch is in the closed circuit position, but which is readily releasable by the initial movement of the operating member during the circuit opening operation. Our improved latching means moves in a direction at right angles to the normal plane of motion of the blade and thereby assures that the magnetic reactions set up by the flow of current through the switch shall not effect

any undesired release of the blade by the latching means during the operation of the switch.

In addition, our improved latching structure and operating assemblage is readily adaptable to switches of almost any capacity, the latch releasing means being so arranged that any number of latches may be released substantially as readily as a single latch. By the provision of cam surfaces on the latch and the latch releasing means, positive movement of the latch is assured, even under the most adverse weather conditions, and in addition, the structure is inherently so arranged that the blade assemblage is subjected to a prying action by the movement of the latch releasing means during each opening operation of the switch. Also our improved latch is particularly suitable for use with double-throw switches, the same latch releasing means being adaptable to operate separate latches disposed adjacent either of the two cooperating contacts for the blade means.

While in accordance with the patent statutes we have disclosed the structural features of a preferred embodiment of our invention, it is to be understood that many of the principles disclosed are capable of wide application without departing from the principles of the invention. It is our desire, therefore, that the language of the accompanying claims shall be accorded the broadest reasonable construction and that our invention shall be limited only by what is expressly stated therein and by the prior art.

We claim as our invention:

1. In an electric switch, a pair of spaced conducting members, a movable blade means for cooperating therewith to open and to close the electrical circuit through said switch, at least a portion of said blade means having an opening formed therein, an operating member supported on said blade member, and a single latch member having a portion which is adapted to engage said opening when said blade means is in the closed-circuit position, said operating member having a portion which extends into said opening for directly engaging and moving said latch member to effect the release of said blade means during each opening operation of said switch.

2. In an electric switch, a pair of spaced insulators, a blade means supported for swingable movement upon one of said insulators, cooperating contact means supported on the other of said insulators, said blade means comprising a flat plate of conducting material which is provided with a cutout portion adjacent one end thereof, a single, pivoted latch supported on said other insulator and movable to engage said cutout portion when said blade means is in the closed-circuit position, and an operating member which is supported on said blade means adjacent said cutout portion and which is provided with a portion adapted to extend into said cutout portion for directly engaging and moving said latch to effect the release of said blade means during each opening operation of said switch.

3. In an electric switch, spaced contact members, a flat blade pivotally supported upon one of said contact members for swingable movement into and out of engagement with said other contact member, said blade having an opening cut therein adjacent the unsupported end, a single latch member pivotally supported adjacent said other contact member and movable substantially at right angles to the normal plane of movement of the blade member to engage the cutout portion and thereby restrain said blade member

against movement, means biasing said latch member to the latched position and an operating member supported on said blade, said operating member having a portion extending into said opening which portion is provided with a cam surface for directly engaging a similar cam surface forming a part of said latch member, said cam surfaces being so arranged that said latch member is moved by said operating member so as to release said blade during the initial stages of the switch opening operation.

4. In a double-throw electric switch, a pair of spaced conducting members, a blade means movable into and out of engagement with either of said conducting members for opening and for closing the electrical circuit through said switch, at least a portion of said blade means comprising means having an opening formed therein, an operating member supported upon said blade member, and a single latch member which is supported adjacent each of said spaced conducting members, each of said latch members being individually adapted to engage said opening when said blade means has been moved into engagement with the adjacent conducting member, said operating member having a portion which extends into said opening for directly engaging and moving the adjacent latch member to effect the release of said blade means during the initial stages of each opening operation of said switch.

5. In an electric switch, a plurality of separate blade members, means for supporting said blade members adjacent one end thereof for swingable movement to open and to close the electrical circuit through said switch, at least some of said blade members having openings cut therein adjacent their unsupported ends, a plurality of separate latch members, each of which is adapted to engage one of said openings when said switch is in the closed-circuit position, and a single operating member supported upon said blade members for simultaneously moving all of those members during the operation of said switch, said operating member having portions which are adapted to extend into said openings in said blade members for directly engaging and moving the adjacent latch member to effect the release of said blade members by said latch members during the initial stages of each switch-opening operation.

6. In a double throw switch, a pair of spaced conducting means, a cooperating blade means which comprises a plurality of separate blade members, means for supporting said blade members adjacent one end thereof for swingable movement to open and to close the electrical circuit through said switch, at least some of said blade members having openings cut therein adjacent their unsupported ends, a plurality of separate latch members one of which is adapted to engage one of said openings in said blade members when said blade means has been moved into engagement with either of said spaced conducting means, and a single operating member supported upon said blade members for simultaneously moving all of those members during the operation of said switch, said operating member having portions which are adapted to extend into said openings in said blade members directly engaging and moving the adjacent latch member to effect the release of said blade members by said latch members during the initial stages of each switch-opening operation, regardless of which closed circuit position said blade

means is in at the beginning of the switch-opening operation.

7. In an electric switch, a pair of spaced conducting members, a movable blade member for cooperating therewith to open and to close the electrical circuit through said switch, at least a portion of said blade member having an opening formed therein, an operating member supported upon said blade member so as to be movable a predetermined distance with respect thereto, and a latch means having a portion which is adapted to engage said opening when said blade member is in the open circuit position, said operating member having a portion which extends into said opening for automatically effecting the release of said latch means and for producing a prying action tending to initiate the movement of said blade member toward the open circuit position during each operation of said switch.

20 8. In an electric switch, a pair of spaced conducting members, a movable blade member cooperating therewith to open and to close the electrical circuit through said switch, said blade member comprising a substantially flat plate of conducting material which is movable in a plane substantially parallel to the opposed faces thereof, and which is provided with a cutout portion adjacent one end thereof, a latch means having a portion adapted to extend into said cutout portion when said blade is in the closed circuit position, and an operating member which is pivotally supported on said blade member so as to be movable a predetermined distance with respect thereto, and which is provided with a portion which extends into said cutout portion for automatically effecting the release of said latch means and for exerting a prying action tending to initiate movement of said blade member toward the open circuit position during each operation of 40 said switch.

9. In an electric switch, spaced contact members, a substantially flat blade member supported upon one of said contact members for swingable movement into and out of engagement with the other contact member, said blade member having an opening cut therein adjacent the unsupported end, a latch member supported adjacent said other contact member and movable substantially at right angles to the normal plane of movement of said blade member to engage said opening, and an operating member supported on said blade so as to be movable a predetermined amount with respect thereto, said operating member having a portion extending into said opening for engaging said latch member in order to effect its release when said operating member is moved relative to said blade member during each opening operation of said switch, said operating member causing said latch member to release said blade member during the initial portion of its possible movement relative to said blade member, and, during the final portion of its possible movement with respect to said blade member, exerting a prying action tending to initiate movement of said blade member toward the open circuit position.

10. In an electric switch, a pair of spaced conducting members, a substantially flat blade member which is supported for swingable movement in a substantially fixed path, for cooperating therewith to open and to close the electrical circuit through said switch, said blade having an opening cut therein adjacent the unsupported end, a latch member supported adjacent one of said contact members and movable at substan-

tially right angles to the normal plane of movement of the blade member to engage said cutout portion and thereby restrain said blade member against movement, means biasing said latch member to the latched position, and an operating member supported upon said blade so as to be movable a predetermined amount with respect thereto, said operating member having a portion extending into said opening, which portion is provided with a cam surface for cooperating with a similar cam surface forming a part of said latch member in order that said latch member shall be moved so as to release said blade member when said operating member is moved relative to said blade member during each opening operation of said switch, said operating member causing said latch member to release said blade member during the initial portion of its possible movement with respect to said blade member, and, during the final portion of its possible movement with respect to said blade member, exerting a prying action tending to initiate movement of said blade member toward the open circuit position.

11. In a double throw electric switch, a pair of spaced contact members, a pivotally supported blade which is swingable into and out of engagement with either of said contact members, said blade having an opening cut therein adjacent the unsupported end, a pivotally supported, spring biased latch positioned adjacent each of said spaced contact members and movable substantially at right angles to the normal plane of movement of said blade, either of said latch members being adapted to engage said cut-out portion and thereby restrain said blade from movement when that member has been moved into engagement with either of said contact members, and an operating member supported upon said blade so as to be movable a predetermined amount relative thereto, said operating member having a portion extending into said opening, which portion is provided with a cam surface and is adapted to cooperate with a similar cam surface forming a part of each of said latch members, said opening being of sufficient size that the initial movement of said operating member relative to said blade during each opening operation of said switch effects the release of the adjacent latch member and the final portion of the possible relative movement of said latch member with respect to said blade member produces a prying action tending to initiate movement of said blade member toward the open circuit position.

12. In an electric switch, a pair of spaced, stationary insulator columns, a contact supported upon one of said insulator columns, a substantially flat blade pivotally supported upon the other of said insulator columns for swingable movement into and out of engagement with said contact to open and to close the electrical circuit through said switch, said blade having an opening cut therein adjacent the unsupported end, a pivotally supported spring biased latch positioned adjacent said contact member and movable substantially at right angles to the normal plane of movement of said blade to engage said cut-out portion and thereby restrain said blade against movement, and an operating lever pivotally supported intermediate its ends upon said blade and movable a predetermined amount with respect thereto, said operating lever having an outwardly projecting portion, formed integral therewith, which extends into said open-

ing from the side opposite to that which said latch enters, this portion having a cam surface for cooperating with a similar cam surface forming a part of said latch member in order that said latch member shall be moved so as to release said blades when said operating lever is moved relative to said blade during each opening operation of said switch, said operating lever ef-

fecting the release of said latch during the initial portion of its possible movement with respect to said blade and, during the final portion of its movement with respect to said blade, exerting a prying action tending to initiate movement of said blade toward the open circuit position.
